Application filed October 7, 1893. Serial No. 487,518. Term of patent 3½ years.

To all whom it may concern:

Be it known that I, CHARLES BOOZE, a citizen of the United States, residing at Buffalo, in the county of Erie and State of New York, have invented and produced a new and original Design for Wall Paper, of which the following is a specification.

The design consists of a series of ornaments of the rococo style, with a festoon of flowers and leaves attached to each side of said ornament and a group of flowers and leaves placed at the top of each ornament as represented in the accompanying drawing. These ornaments are arranged at suitable distances apart over the surface of the hanging. In the upper

portion of the design which forms the border, these rococo style ornaments are connected by festoons of flowers and leaves as represented in the drawing.

What I claim is—

1. The design for wall paper herein shown and described.
2. In the design for wall paper the border herein shown and described.

Witness my hand this 2d day of October, 1893.
